METHOD AND MEANS FOR CONTROLLING AGITATION OF THE CONTENTS OF A CRUCIBLE MEMBER OF AN INDUCTION FURNACE

Johann Peter Rohn, Kolin-Buchforst, Germany, assignor to Firma Russ-Elektrofen K. G. Kolin, Kolin-Bayenthal, Germany

Application February 18, 1954, Serial No. 411,216

Claims priority, application Germany February 20, 1953

11 Claims. (Cl. 13—27)

This invention relates to an improved induction furnace and more particularly to an improved grooveless induction furnace operable on normal power frequencies.

Grooveless induction furnaces operable on normal power frequencies are known in the prior art. Crucibles for such furnaces are normally made of steel or ceramic material. This type of furnace has not been used in the past to any great extent because the forces generated by the induction coil or coils often cause such great agitation of the molten fluid within the crucible that this fluid is caused to rise over the rim of the crucible and splatter outside of the crucible.

In order to avoid the above difficulty, prior art furnaces have been constructed with three induction coils energized by three phase current. Different of the phases are interrupted in a random or arbitrary manner so that at any given time only one or two of the coils are energized and in succeeding periods of time different ones of the coils are energized. In other arrangements employing a plurality of coils, the coils are energized in some regular order by various switching arrangements, rheostats, etc.

The above methods have several disadvantages. One is that the life span of the oven lining is seriously impaired because of the rapid, transient changes in flux density. Furthermore, the prior art methods require, in order to switch energy from one coil to another, various tapped transformer arrangements, chokes, rheostats and other cumbersome and expensive auxiliary control devices.

It is an object of the present invention to provide an induction oven operable on normal power frequencies such as 50 or 60 cycles which has none of the foregoing disadvantages.

In accordance with the invention there is provided an induction furnace which mainly consists of the combination of a crucible member and a coil member disposed about the crucible member for heating the contents thereof. Supporting means are provided for the crucible member and the coil member, one of said supporting means being movable with respect to the other of said supporting means. When one of said supporting means is moved relative to the other, the agitation produced in the contents of the crucible is controlled and the contents are prevented from overflowing the crucible.

In one preferred embodiment of the invention, the crucible is mounted on a fixed base and the coil together with its iron core which surrounds the crucible is moved up and down relative to the crucible.

In a second preferred embodiment of the invention the crucible is mounted on a movable support and the coil and its core mounted on a fixed support. A drive mechanism is provided for moving the crucible in axial direction relative to the coil and its core.

In a third preferred embodiment of the invention the crucible and the core are mounted on a fixed base and the coil which energizes the core is driven by a drive mechanism.

In a final embodiment of the invention, the coil is movable relative to both the crucible and the core from a position in which the coil is entirely retracted between the core assembly and the crucible to a second position wherein the coil is at least partially outside of the core.

The novel features which are considered as character-

2

istic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a cross-sectional view of an induction furnace in accordance with one embodiment of the invention;

Fig. 2 is a cross-sectional view of an induction furnace in accordance with another embodiment of the invention;

Fig. 3 is a cross-sectional view of an induction furnace in accordance with a third embodiment of the invention; and

Fig. 4 is a cross-sectional view of an induction furnace in accordance with a fourth embodiment of the invention.

In the various figures, like numerals refer to like elements.

Referring now to Fig. 1, there is shown a crucible 11 mounted on a base 14 and surrounded by a coil 12 and magnetic core 13. The core and coil are slidably supported on the crucible by means of a movable supporting arm 16. This supporting arm is movable in the directions indicated by the arrows by means of a drive mechanism 15.

Fig. 2 shows a crucible 11 and a magnetic core 21, both the core and crucible being supported on a fixed base 22. The core is provided with a pair of apertures at the bottom end thereof through which a movable supporting structure 24 passes. Coil 12 surrounds the crucible and is movable in the directions indicated by the arrows by means of drive mechanism 23 which is coupled to the coil by the movable support 24.

In the embodiment illustrated in Fig. 3, coil 12 and magnetic core 13 are mounted on a fixed base 20. Crucible 11 is mounted on movable support 17 which is driven in the directions indicated by the arrows by means of drive mechanism 19 and mechanical connection 18.

A fourth embodiment of the invention is illustrated in Fig. 4. In this embodiment, the magnetic core 25 has an open portion at the bottom end thereof through which the coil 12 fits. The magnetic core and crucible are mounted on a fixed base and coil 12 is mounted on a movable support 28. The coil is driven by means of drive mechanism 27 from a first position in which the coil is entirely retracted within the magnetic core to a second position in which the coil is outside of the magnetic core.

In the operation of the invention illustrated in Figs. 1—4, relative movement is caused between the crucible and the coil in the manner indicated in order to control the operation of the furnace. Such movement is usually periodic and between two limits, however, the invention is also applicable to aperiodic movement. Because of the relative movement of the parts, the agitation of the molten fluid within the crucible is kept within acceptable limits and the fluid is prevented from overflowing the crucible. In the embodiment illustrated in Fig. 4 the furnace may, in effect, be shut off by causing the coil 12 to move entirely or almost entirely outside of the magnetic core so that the heat induced is at a minimum. Similarly, in Fig. 3 the same effect may be achieved by moving the crucible outside of the core and coil.

In the above-described embodiments, no details are given for the drive mechanism since such mechanisms are well known. The dashed lines 16, 18, 24 and 28 may, for example, merely comprise a shaft. The shaft may be driven by means of a piston cylinder arrangement which may be powered by a motor or which may even be driven by a hand crank. Many other types of drive mechanisms are equally applicable to the invention.

The various base members are usually constructed of some sort of heat insulating material so that no heat is conducted away from the crucible. The illustration, of course, is merely schematic since almost any shape of base member would do provided a drive mechanism could be conveniently connected to either the crucible or coil.

The various magnetic cores are made of iron laminations in the usual manner.

Although no power source is illustrated, it is to be understood that the coils are energized by normal alternating current at a frequency such as 50 or 60 cycles. It is also to be understood that although a single coil is illustrated, it may be preferable in some cases to use two or more coils and these coils may be driven either in synchronism or independently.

The crucible illustrated in the various figures may be made from steel or ceramic material.

It will be understood that each of the elements described above, or two or more together, may also find a useful application in other types of induction furnaces differing from the types described above.

While the invention has been illustrated and described as embodied in an induction furnace operable at normal power frequencies, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. An induction furnace, comprising, in combination, a crucible member; an induction coil member surrounding said crucible member for heating the contents of said crucible member; and drive means coupled to said coil member for moving it relative to said crucible member, whereby the agitation produced in the contents of said crucible member due to the inductive heating thereof is controlled and said contents are prevented from overflowing said crucible member.

2. An induction furnace, comprising, in combination, a crucible member; an induction coil member surrounding said crucible member for heating the contents of said crucible member; and drive means coupled to said crucible member for moving it relative to said coil member, whereby the agitation produced in the contents of said crucible member due to the inductive heating thereof is controlled and said contents are prevented from overflowing said crucible member.

3. An induction furnace, comprising, in combination, a fixed support and a movable support; a crucible member mounted on said fixed support; an induction member comprising a coil surrounding said crucible member, and a magnetic core for said coil coaxial about said coil, said induction member being secured to said movable support and being slidably mounted on said crucible member; and a drive mechanism connected to said movable support for moving said induction member in axial direction relative to said crucible member, whereby the agitation produced in the contents of said crucible member due to the inductive heating thereof is controlled and said contents are prevented from overflowing said crucible member.

4. An induction furnace, comprising, in combination, a crucible member mounted on a fixed support; an induction member comprising a magnetic core surrounding said crucible member and mounted on said fixed support, there being a space between said magnetic core and said crucible member, and a coil surrounding said crucible member and located in said space between said crucible member and said magnetic core, said coil being in slidable engagement with said crucible member and being movable in axial direction; and a drive mechanism connected to said coil for moving the same in axial direction relative to said crucible member and said magnetic core, whereby the agitation produced in the contents of said crucible member due to the inductive heating thereof is controlled and said contents are prevented from overflowing said crucible member.

5. An induction furnace comprising, in combination, an induction member including a coil and a magnetic core coaxial with said coil, said induction member being mounted on a base member; a movable supporting member; a crucible member located within said induction member and supported by said movable supporting mem-

ber; and a drive mechanism connected to said movable supporting member for moving said crucible member in axial direction relative to said induction member, whereby the agitation produced in the contents of said crucible member due to the inductive heating thereof is controlled and said contents are prevented from overflowing said crucible member.

6. An induction furnace comprising, in combination, a crucible member mounted on a fixed support; a magnetic core mounted on said fixed support and surrounding said crucible member, there being a space between said crucible member and said magnetic core; a coil surrounding said crucible member and located in the space between said crucible member and said magnetic core, said coil being in slidable engagement with said crucible member and being movable in axial direction from a first position in which said coil surrounds a portion of said crucible member to a second position in which the coil is moved entirely outside of the space between said magnetic core and said crucible member; and drive means connected to said coil for moving it between said first and second positions, whereby the agitation produced in the contents of said crucible member due to the inductive heating thereof is controlled and said contents are prevented from overflowing said crucible member.

7. An induction furnace comprising, in combination an induction member including a coil and a magnetic core coaxial with said coil, said induction member being mounted on a base member; a movable supporting member; a crucible member located within said induction member and supported by said movable supporting member; and a drive mechanism connected to said movable supporting member for moving said crucible member in a periodic manner in axial direction relative to said induction member, whereby the agitation produced in the contents of said crucible member due to the inductive heating thereof is controlled and said contents are prevented from overflowing said crucible member.

8. An induction furnace, comprising, in combination, a crucible member; an induction coil member surrounding said crucible member for heating the contents of said crucible member; supporting means for supporting said crucible member; supporting means for supporting said coil member, at least one of said supporting means being movable relative to the other of said supporting means; and drive means connected to the movable one of said supporting means for moving it in a periodic manner relative to the other of said supporting means.

9. An induction furnace, comprising, in combination, a crucible member; an induction coil member surrounding said crucible member for heating the contents of said crucible member; supporting means for supporting said crucible member; supporting means for supporting said coil member, at least one of said supporting means being movable relative to the other of said supporting means; and drive means connected to the movable one of said supporting means for moving it in a periodic manner between two limits relative to the other of said supporting means.

10. In an induction furnace having a crucible member and an induction coil member surrounding said crucible member for heating the contents of said crucible member, a method for controlling the agitation produced in said contents comprising the step of moving one of said members relative to the other of said members in a periodic manner.

11. In an induction furnace having a crucible member and an induction coil member surrounding said crucible member for heating the contents of said crucible member, a method for controlling the agitation produced in said contents comprising the step of moving one of said members relative to the other of said members in a periodic manner between two positions, one in which the induction coil member surrounds the top portion of said crucible member, and the other in which the induction coil member surrounds the bottom portion of said crucible member.
